UNITED STATES PATENT OFFICE.

ALPHONSE MATHERN, OF ZOLLIKON, NEAR ZURICH, SWITZERLAND.

MACHINE FOR THE MECHANICAL PRODUCTION OF THE COVERS FOR PNEUMATIC TIRES.

1,186,591.

Specification of Letters Patent. Patented June 13, 1916.

Application filed August 16, 1913. Serial No. 785,087.

To all whom it may concern:

Be it known that I, ALPHONSE MATHERN, a citizen of the Republic of France, residing at Zollikon, near Zurich, in the Canton of Zurich, Republic of Switzerland, have invented certain new and useful Improvements in Machines for the Mechanical Production of the Covers for Pneumatic Tires; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to an improved method of and a machine for the mechanical production of the covers for pneumatic tires.

It is usual to provide covers for pneumatic tires with plies or layers of canvas or similar fabric coated with rubber and stretched over a core or forming-ring with the aid of radially advanced forming or spinning rolls.

According to my invention, the fabric serving to provide the plies or layers is stretched along the median portion previous to passing on to the forming-ring upon which it is further stretched and applied by smoothing rollers arranged to travel over an eccentric path on the forming-ring. For this purpose I provide a machine which is automatic in action for stretching, applying and smoothing the fabric and for imparting eccentric travel to the smoothing rollers which are carried on a vertically swinging arm.

The accompanying drawings show the machine and various detail parts for carrying out the work.

Figure 1, is a front elevation of the complete machine. Fig. 2 is a plan with a portion in section along the line A—B of Fig. 1. Fig. 3 is an elevation of one of the gages for applying the beads. Fig. 4, is a section of said gage on the line C—D of Fig. 3. Fig. 5 is an elevation of the carrier for said gage. Fig. 6, is a section through the carrier on the line E—F of Fig. 5. Fig. 7, is an elevation of the opposite gage. Fig. 8, is a section on line G—H of Fig. 7. Fig. 9, is a transverse section, drawn to a larger scale, through a portion of the forming ring

on the line J—K. Figs. 10, 11 and 12, are sections showing the work at three different stages.

On a suitable bed 1 are mounted various shafts, the shaft 2 of which carries at one end the forming ring 16, while the shafts 3 and 4 serve in driving the main shaft 2. A shaft 5 drives eccentric arms in connection with smoothing rollers 25 for sticking down the edges and adjacent portions of the material of the cover, and shafts 6 and 7 serve for driving the stretching device as also the small rollers on the shafts 8, 9 and 10.

The step pulley 11 is driven from an overhead shaft and is fast on the shaft 3 which through the intervention of bevel wheels 12 and 13 drives the shaft 4 upon which is fixed a worm, not seen. The worm drives a wormwheel 14 which drives the main shaft 2 through the intervention of a toothed clutch 15. With this mechanical arrangement, the forming ring makes one revolution a minute. The peripheral speed of the drum 14, mounted on the shaft 7, is slightly less than that of the forming ring and is controlled by bevel gears 38, shaft 6, and bevel gears 39.

The prepared rubber-coated canvas or like material, previously wound on the drum 19, is prevented from sticking together by being wound up in the known manner with an intervening strip of ordinary material. The drum 19 is keyed on its shaft 9 and the latter is caused to rotate by reason of the drawing off of the coated material. On the shaft 9 is fast a strap-pulley 20, the strap driving a similar pulley 21 fast on the shaft 10 which carries a drum 22 for winding up the intermediate strip withdrawn from the coated material on the drum 19 in a manner previously carried out.

For starting the operation, the loose end of the rubber-coated material is taken in flat condition over the guide roller 23 and then under the convex stretching drum 24 and cemented on to the forming ring 16 which is in contact with the former. The machine is then started so that the ring 16 draws the material from the drum 24 on to the upper portion of the said ring 16, the pulling action and the adhesiveness of the material imparting to the latter a tendency to cling to the drum 24 which has a definite peripheral speed which is less than 110

the peripheral speed of the forming ring 16. Owing to the difference in the speeds and convex surfaces of the ring 16 and drum 24, the material is caused to stretch at the point of contact between the drum 24 and ring 16. The speeds of said drum and ring remain constant and consequently the stretching of the material will be constant. For altering the stretching of the material, it is necessary to use another drum having a different peripheral speed. During the operation it is impossible to have irregular stretching of the material.

By this system of operating, the coated material is simultaneously stretched and gummed to the other portion of the ring 16 so that only the edge portions of the said material remain loose and strongly ruffled or puckered along the sides of the ring 16. During the rotation of the latter, the material is brought under the rollers 25 which run along an eccentric curve 29, Fig. 1, at both sides of the ring 16. For this purpose, the rollers 25 are mounted on a swinging arm 26 which is controlled through the intervention of a connecting rod 27 operated by a crank disk 28 on shaft 5 which is driven by pulleys 40. The curve traversed by the rollers 25 pass from the edges toward the periphery and back so that the side portions of the material are stretched and cemented to the ring in a regular manner, the rollers being strongly pressed against the latter by springs 41. The progressive condition of the curve enables the rollers to completely smooth and press the material. In this manner the material is secured in position and by the continued rotation of the ring 16, one, two or more layers can be applied at one operation while being automatically stretched, applied and smoothed so as to assume the form indicated at Fig. 10.

It is now necessary to apply the beads according to Fig. 11, for which purpose the following parts are used: The cross 30, Figs. 2, 5 and 6, is permanently retained on the shaft 2 and has in each arm a slot or groove into which the four arms of the gage 31 are secured, see Figs. 3, 4 and 9. The slots may be so arranged as to slip the arms in sidewise and so secure or release same by turning the gage in the one or the other direction. After the gage 31 has been fixed to the cross 30, the latter is moved along the shaft 2 close against the ring 16, whereon a freely falling pawl enters a rack provided in shaft 2 and prevents shifting back. The outer gage 32 is then applied to the projecting end of the shaft 2 and fixed by a screw nut 33 or otherwise suitably, see Figs. 7, 8 and 9. The two gages are secured together by spring-controlled hooks 34, 35. The clutch 15 is then set so as to leave the wormwheel 14 free and to get the drive through the toothed wheel 17 and pinion 18.

With this direct drive a speed of about 30 revolutions a minute is imparted to the shaft 2. The two beads can now be cemented on, they being accurately centered by the two gages. It is easy to press the beads on to the material by means of a hand roller or by a tool provided on the machine.

After the beads have been applied, it is necessary to finish the work according to the manner illustrated in Fig. 11. For this purpose the gage 32 is removed and gage 31 is shifted back, while the machine is thrown back to slow speed in order that two or more coverings of material may be applied according to Fig. 12, the work being carried out in the same manner as has been described in connection with the inner layers.

What I claim is:

1. A machine for manufacturing covers for pneumatic tires from rubber coated material comprising in combination a convex drum, a forming ring, means for feeding the rubber coated material, in contact with said drum, to said forming ring, said forming ring and drum being in close proximity so that the material is pressed between them and means for positively controlling the speed of said drum so that it operates at a less peripheral speed than the peripheral speed of the forming ring.

2. A machine for manufacturing covers for pneumatic tires from rubber coated material comprising a forming ring, means for feeding the rubber-coated material to said ring, a single smoothing device on each side of said ring, and means for moving said smoothing devices along the sides of the forming ring in an arc which is eccentric to the ring and extends across the whole depth of said sides.

3. A machine for manufacturing covers for pneumatic tires from rubber coated material comprising a forming ring, means for feeding the rubber coated material to said ring, a pair of spring-pressed smoothing rollers arranged one on each side of said ring and carried on an arm pivoted eccentrically to said ring, and means for oscillating said arm so that the rollers move across the sides of the forming ring in an arc which is eccentric to the ring and extends across the whole depth of said sides.

4. In a machine for manufacturing covers, with bead members, for pneumatic tires, a shaft, a forming ring carried thereon, a gage for centering the bead members consisting of an annular gage axially adjustable and retainable on said shaft, and a second annular gage adapted to be coupled to the first named annular gage by means of spring-hooks.

5. In a machine for manufacturing covers, with bead members, for pneumatic tires, a shaft, a forming ring carried thereon, having a projecting flange on each side of its
